UNITED STATES PATENT OFFICE.

NELSON H. TUNKS, OF TOLEDO, OHIO, ASSIGNOR OF ONE-HALF TO FRANK C. MOTTER, OF SAMF PLACE.

DESIGN FOR AN UNCOUPLING-ARM FOR AUTOMATIC CAR-COUPINGS.

SPECIFICATION forming part of Design No. 34,581, dated May 28, 1901.

Application filed April 29, 1901. Serial No. 58,094. Term of patent 7 years.

To all whom it may concern:

Be it known that I, NELSON H. TUNKS, of Toledo, county of Lucas, and State of Ohio, have invented a certain new Design for an Uncoupling-Arm for Automatic Car-Couplers; and I do hereby declare that the following is a full, clear, and exact description thereof, which will enable others skilled in the art to which it appertains to make and use the same, reference being had to the accompanying drawings, and to the figures of reference marked thereon, which form part of this specification.

This invention relates to an uncoupling-arm for attachment to the inner end of the operating-lever of an automatic car-coupler; and it consists in the novel configuration thereof.

In the drawings, Figure 1 is an elevation of the uncoupling-arm. Fig. 2 is a top plan view of the same. Fig. 3 is a cross-section taken on line $x-x$. Fig. 4 is a cross-section on line $y-y$.

The uncoupling-arm, as shown in the drawings, embodies a disk-shaped fastening end 1 and a smaller disk-shaped free end 2, the same being joined by a tapering web 3, upon the flattened side faces of which are longitudinal ribs 4, also joining the ends 1 and 2. Upon the sides of the fastening end are square bosses 5, through which the end 1 extends a square perforation 6. In the free end 2 is provided a transverse circular perforation 7.

What I claim, and desire to secure by Letters Patent, is—

The design for an uncoupling-arm for automatic car-couplers, substantially as herein shown and described.

In testimony that I claim the foregoing as my own I affix my signature in presence of two witnesses.

NELSON H. TUNKS.
